Primary Examiner — Patricia A Palasik(74) *Attorney, Agent, or Firm* — Horst M. Kasper, Esq.(57) **CLAIM**

The ornamental design for an actuator, as shown and described.

DESCRIPTION

FIG. 1 is a right side elevational view of the actuator showing my new design;

FIG. 2 is a front elevational view thereof;

FIG. 3 is a rear elevational view thereof;

FIG. 4 is a left side elevational view thereof;

FIG. 5 is a bottom plan view thereof;

FIG. 6 is a top plan view thereof;

FIG. 7 is a front perspective thereof; and,

FIG. 8 is a front bottom perspective thereof.
